UNITED STATES PATENT OFFICE.

WILLIAM F. LAUTENSCHLAGER, OF CINCINNATI, OHIO, ASSIGNOR TO LORENZ MUTHER, OF NEWTON, MASSACHUSETTS.

KNOTTED STITCH AND METHOD OF MAKING THE SAME.

1,284,911.

Specification of Letters Patent. Patented Nov. 12, 1918.

Application filed October 26, 1914. Serial No. 868,654.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Knotted Stitches and Methods of Making the Same, of which the following is a specification.

10 It is the object of my invention to provide a knotted stitch arranged to attach an object to fibrous or fabric material, which object may be instanced as a button, or as another or other fibrous or fabric piece or 15 pieces of material, and which latter may be superposed upon the first-named fabric or fibrous material to which it is attached or be arranged in edge to edge relation therewith.

20 My invention may be employed for securing a plurality of pieces of material together in operations usually known as riveting or tacking in the shoe and sewing industries; or in reinforcing operations, in attaching shank-eye buttons in place, for instance, on 25 button shoes, in attaching flat buttons having eyes through the body of the button, for instance, in attaching buttons to overalls, underwear, and for other purposes, for 30 stapling the insoles of shoes to uppers, for tacking pieces together edge to edge, as in the making of heel-lifts, and for similar and other purposes.

35 It is the object of my invention to provide a novel knotted stitch, and method of making the same, and to provide a novel knotted stitch which is simple and readily formed and which will hold the objects together in close contact and be so formed that the knot prevents loosening of the 40 stitch, and further to provide the knot in such a position as to extend but slightly beyond the plane of the material.

45 It is a further object of my invention to provide a knotted stitch which is independent of other stitches, so that it may be employed in relations where it is desirable to form only a single stitch or but few stitches, arranged to hold two objects together in such manner as to avoid unraveling of the 50 stitches.

The invention will be further readily understood from the following description and claims, and from the accompanying drawings.

The knotted stitch may be formed manually or by machinery, as may be desired, although in the ordinary course of manufacture the stitch will be more generally accomplished by suitable machinery or combination of devices acting on the thread. I have 55 not herein shown any mechanism for manipulating the thread in accomplishing the desired results, as any mechanism suitable for the purpose may be employed.

I have, in the drawings, illustrated various stages in the course of the formation of the knotted stitch, these stages being selective or arbitrary stages selected at points in the formation of the knotted stitch which will most clearly show the manipulation of 60 the thread, it being understood that, especially when the knotted stitch is formed by machinery, the operations or manipulations 65 preferably take place in a continued and uninterrupted series of steps for forming the 70 knotted stitch.

I have exemplified my invention as employed in securing together two superposed pieces of material; in attaching a shank-eye button to a piece of material; in attaching 80 a flat button to a piece of material; and, in stapling two pieces together in edge to edge relation, from which the application of the 85 knotted stitch in other relations will be readily perceived.

In the drawings:

Figure 1 is a perspective view showing a primary loop of the thread received through two superposed layers of material, the latter shown in vertical section taken on the line of 90 the stitch and partly broken away.

Fig. 2 is a similar view showing the primary loop flexed in the line of the stitch preparatory to being received reversely through 95 the material.

Fig. 3 is a similar view with the loop received reversely through the material.

Fig. 4 is a similar view showing a supplemental loop received through the primary loop, the supplemental loop being formed by 100 one of the stretches of the thread.

Fig. 5 is a similar view with the slack drawn out of the primary loop.

Fig. 6 is a similar view showing the other stretch of the thread received through the 105 supplemental loop.

Fig. 7 is a bottom view of the same.

Fig. 8 is a perspective view of the stitch

- with the material shown in vertical section on the line of the stitch, the secondary stretch and the supplemental loop being partly drawn taut.
- 5 Fig. 9 is a similar view with the knot of the stitch formed, and indicating snippers for trimming the free ends of the stitch.
- Fig. 10 is a bottom view of the same, with the snippers omitted.
- 10 Fig. 11 is a perspective view of the knotted stitch with the superposed layers of material indicated in dotted lines.
- Fig. 12 is a perspective view showing the primary loop of the stitch received through 15 the material and through the shank-eye of a button, the material being shown in vertical section taken on the line of the stitch and partly broken away.
- Fig. 13 is a similar view showing the primary loop flexed in the line of the stitch 20 preparatory to being received reversely through the material.
- Fig. 14 is a similar view with the primary loop received reversely through the material.
- 25 Fig. 15 is a similar view showing the knotted stitch formed.
- Fig. 16 is a perspective view showing the primary loop received through the material 30 and through one of the holes of a pierced button, the material being shown in vertical section taken on the line of the stitch and partly broken away.
- Fig. 17 is a similar view showing the primary loop flexed in the line of the stitch 35 preparatory to being received reversely through another hole of the button and the material.
- Fig. 18 is a similar view with the primary loop received reversely through said other 40 hole of the button and the material.
- Fig. 19 is a similar view showing the knotted stitch formed.
- Fig. 20 is a perspective view showing the primary loop received through one of two 45 pieces of material arranged edge to edge, the pieces of material being shown in vertical section taken on the line of the stitch and partly broken away.
- 50 Fig. 21 is a similar view showing the primary loop flexed on the line of the stitch preparatory to being received reversely 55 through the other piece of material.
- Fig. 22 is a similar view showing the primary loop received reversely through said other piece of material; and,
- Fig. 23 is a similar view showing the knotted stitch attaching two pieces of material together in edge to edge relation.
- 60 Figs. 1 to 11 inclusive illustrate a riveting, tacking or stapling operation for securing together two superposed pieces of material designated at 11 and 12. It will be assumed for convenience of description, that 65 the stitch is being formed by suitable mecha-
- nism, in which the thread, designated generally as 13, is supplied from a suitable bobbin or spool, and that the stretch 14 of the thread is the supply stretch of the thread, and the stretch 15 of the thread is the initial stretch of the thread, which may be suitably initially held, as by a pair of jaws 16.
- At the point where the stitch to be formed is located, the thread is passed through holes 17 and 18 in the superposed layers of material, suitably formed in the material either concurrently with or independently of the passing of the thread through the holes, depending on whether an eye-needle or a hook-needle is employed for the purpose. 75 The thread is received through the holes for forming a primary loop 19, (see Fig. 1).
- The primary loop is then deflected lengthwise of the line of the stitch as indicated at 20, (see Fig. 2). This may be accomplished either by feeding the material in the direction of the arrow *a* or by deflecting the loop, the material remaining stationary, or by both these movements. The primary loop is received reversely through the material through the holes 21 and 22 in the superposed layers of material (see Fig. 3), distanced from the holes 17 and 18 a distance corresponding to the length of the stitch. The primary loop may be either pulled or 80 pushed through the holes 21 and 22, depending on the instrument employed.
- 90 A supplemental loop 23 is formed in one of the stretches of the primary loop and is exemplified as formed in the supply stretch 100 thereof. This supplemental loop is received through the primary loop (see Fig. 4), and is preferably formed in great part by drawing upon the primary loop so as to cause the bight 24 of the primary loop to be drawn 105 close about the primary stretch 25 and the secondary stretch 26 of the supplemental loop (see Fig. 5).
- The other stretch of the primary loop, exemplified as the initial stretch 15 thereof, is 110 received through the supplemental loop (see Figs. 6 and 7), tension being exerted upon the stretch so drawn through the supplemental loop and the secondary or supply stretch 26 of the supplemental loop for 115 drawing upon the primary and supplemental loops, (see Fig. 8), and initiating the knot. A pull, which is preferably a sudden and tense pull, is then exerted upon both ends of the thread of the stitch, exemplified 120 as the primary stretch of the primary loop and the supply stretch of the supplemental loop, which exerts a tension upon the bight 24 of the primary loop and upon the bight 27 of the supplemental loop for forming a 125 bight 28 in the initial stretch of the primary loop, preferably drawing said bight partway into the bight of the primary loop and curving said last-named stretch about the bight of the primary loop as shown by the 130

hitch 29. The stretches of the supplemental loop are further preferably drawn in the form of bights 30, 31, partway into the hole 22, by the tension exerted upon the bight 24 5 in the primary loop, (see the knot as formed in Figs. 9, 10 and 11).

The stretches of the thread extending from the knotted stitch are then cut or snipped adjacent to the knot, as by the snippers 32, 10 33, leaving a slight length of thread however to prevent accidentally unraveling of the knotted stitch.

In Figs. 12 to 15 inclusive, I have illustrated the stitch employed for securing another material as a shank-eye button, in place. The stitch is formed in the same manner as that employed in attaching a plurality of superposed pieces of material together, as illustrated in Figs. 1 to 11 inclusive, the illustration of certain of the steps illustrated in Figs. 1 to 11 being omitted in Figs. 12 to 15, inclusive. Figs. 12, 13 and 20 14, show the manner in which the shank-eye button is received about the primary loop 25 and Fig. 15 shows the completed knotted stitch.

In these figures 111 represents the piece of material or shoe part, for instance the quarter of the shoe, to which the button 112 30 is arranged to be secured. The parts of the knotted stitch in Figs. 12 to 15, inclusive are designated by similar reference numerals employed for designating the knotted stitch parts shown in Figs. 1 to 11 inclusive but 35 raised to the series 100. The primary loop 119 is received through the shank-eye 118 of the button, which may be accomplished concurrently with the passage of the primary loop through the hole 117, or after the 40 primary loop has been received through said hole.

In Figs. 16 to 19 inclusive my invention is illustrated as employed for attaching another material, as a pierced or flat button, to a piece of fabric, the piece of fabric being designated 211 and the flat button being designated 212. The stitch and the parts thereof are similar to the stitch illustrated in Figs. 1 to 11 inclusive and are designated 45 by similar reference numerals raised to the series 200. The fabric 211 may exemplify the trousers band of a pair of overalls, or the button fly of a piece of underwear or similar or other part.

50 In this exemplification the primary loop is received through the hole 217 in the fabric, and through the hole 218 in the button, which may be accomplished concurrently with the passage of the primary loop 55 through the hole 217 or after the primary loop has been received through said hole. The primary loop having received its deflection, as shown at 220, is received reversely through the hole 221 in the button 60 and the hole 222 in the fabric, in manner

similar to the description with reference to the exemplification shown in Figs. 1 to 11, inclusive.

The steps employed for forming the knotted stitch exemplified in Figs. 1 to 11 are 70 also employed in the exemplification illustrated in Figs. 16 to 19 inclusive, the illustration of certain of the steps being however omitted in the latter figures, Figs. 16 to 18, inclusive showing the means for receiving 75 the primary loop through the button holes, and Fig. 19 showing the completed stitch.

In Figs. 20 to 23, inclusive, I have exemplified my invention as employed in securing together two pieces of fibrous material 80 or fabric in edge to edge relation, employed, for instance, in tacking together two pieces of scrap leather for forming intermediate lifts for the heels of boots and shoes. In this exemplification the pieces of material 85 are exemplified at 311 and 312, the stitch and its parts being exemplified by reference numerals similar to the reference numerals employed in Figs. 1 to 11, inclusive, but 90 raised to the series 300.

Illustration of certain of the steps employed in forming the knotted stitch is omitted in Figs. 20 to 23 inclusive, they being repetitions of the steps illustrated in Figs. 4 to 9, inclusive. Figs. 20 to 22 inclusive illustrate the stitch in its relation to the particular purpose illustrated in said figures, showing the primary loop 319 received through the hole 317 in the piece of material 311, deflected laterally across the 100 proximate edges 334 of said strips, and received reversely through the hole 321 in the piece 95 312, the knotted stitch being formed for securing the said pieces in endwise relation as illustrated in Fig. 23.

Having thus fully described my invention, what I claim as new and desire to secure by Letters Patent is:

1. The method of attaching a button to material which consists in passing a loop of 110 thread comprising a pair of stretches through the material, through the attaching portion of the button and in reverse direction through the material for forming a primary loop, passing one of the stretches 115 of said thread through said primary loop as a supplemental loop, passing the other of the stretches of said thread through said supplemental loop, and drawing the thread taut for forming a knot comprising the 120 bights of said loops and said other of said stretches in knotted relation.

2. The method of attaching a button to material which consists in passing a loop of thread comprising a pair of stretches 125 through the material, through the attaching portion of the button and in reverse direction through the material for forming a primary loop, passing one of the stretches of said thread through the bight portion of 130

said primary loop as a supplemental loop, drawing upon said stretch forming said supplemental loop for drawing up said primary loop whereby its bight is drawn across the 5 stretches of said supplemental loop, passing the other of the first-named stretches of said thread through said supplemental loop, and drawing upon the outer stretch of said supplemental loop for drawing its bight upon 10 said other of said first-named stretches of said thread.

3. The method of attaching a button to material which consists in passing a loop of thread comprising a pair of stretches 15 through the material, through the attaching portion of the button and in reverse direction through the material for forming a primary loop, passing one of the stretches of said thread through the bight portion of 20 said primary loop as a supplemental loop, passing the other of the stretches of said thread through the bight portion of said supplemental loop, and drawing said thread taut whereby said bights are piled one 25 against the other and said last-named stretch is drawn as a bight partway into said bight of said primary loop.

4. The method of attaching a button to material which consists in passing a loop of 30 thread comprising a pair of stretches through the material, through the attaching portion of the button and in reverse direction through the material for forming a primary loop, passing one of the stretches of said 35 thread through the bight portion of said primary loop as a supplemental loop, passing the other of the stretches of said thread through the bight portion of said supplemental loop, and drawing said thread taut 40 said bights being piled one against the other, and said last-named stretch drawn as a bight partway into said bight of said primary loop and against the material.

5. The method of attaching a button to 45 material which consists in passing a loop of thread comprising a pair of stretches through the material, through the attaching portion of the button and in reverse direction through the material for forming a 50 primary loop, passing one of the stretches of said thread through the bight portion of said primary loop as a supplemental loop, passing the other of the stretches of said thread through the bight portion of said 55 supplemental loop, and drawing said thread taut, said bights being piled one against the other, said last-named stretch drawn as a bight partway into said bight of said primary loop and against the material, and the 60 stretches of said supplemental loop drawn as bights by the bight of said primary loop partway into the hole in the material through which said primary loop passes.

6. The method of attaching a button to 65 material by means of a single thread which

consists in holding one end of said thread, passing said thread as a loop comprising a pair of stretches through the material, through the attaching portion of the button and in reverse direction through the material for forming a primary loop, passing one of the stretches of said thread through the bight portion of said primary loop as a supplemental loop, passing the other of the stretches of said thread through the bight portion of said supplemental loop, and drawing the thread taut for forming a knot comprising the bights of said loops and said other of said stretches in knotted relation. 70 75

7. The method of attaching a button to material by means of a single thread which consists in holding one end of said thread, passing said thread as a loop comprising a pair of stretches through the material, through the attaching portion of the button 80 and in reverse direction through the material for forming a primary loop, passing one of the stretches of said thread through the bight portion of said primary loop as a supplemental loop, passing the other of the stretches of said thread through the bight portion of said supplemental loop, drawing the thread taut for forming a knot comprising the bights of said loops 85 and said other of said stretches in knotted relation. 90 95

8. The method of forming a knotted stitch which consists in passing a loop of thread comprising a pair of stretches in reverse directions through the material for forming a primary loop, passing one of the stretches of said thread through said primary loop as a supplemental loop, passing the other of the stretches of said thread through said supplemental loop, and drawing the thread taut for forming a knot comprising the bights of said loops and said other of said stretches in knotted relation. 100 105

9. The method of forming a knotted stitch 110 which consists in passing a loop of thread in reverse directions through the material as a primary loop comprising a pair of stretches, passing one of the stretches of said thread through the bight portion of said primary loop as a supplemental loop, drawing upon said stretch forming said supplemental loop for drawing up said primary loop whereby its bight is drawn across the stretches of said supplemental loop, 115 passing the other of the first-named stretches of said thread through said supplemental loop, and drawing upon the outer stretch of said supplemental loop for drawing its bight upon said other of said first-named stretches 120 of said thread. 125

10. The method of forming a knotted stitch which consists in passing a loop of thread in reverse directions through the material as a primary loop comprising a 130

pair of stretches, passing one of the stretches of said thread through the bight portion of said primary loop as a supplemental loop, passing the other of the stretches of said 5 thread through the bight portion of said supplemental loop, and drawing said thread taut whereby said bights are piled one against the other and said last-named stretch is drawn as a bight partway into said bight 10 of said primary loop.

11. The method of forming a knotted stitch which consists in passing a loop of thread in reverse directions through the material as a primary loop comprising a 15 pair of stretches, passing one of the stretches of said thread through the bight portion of said primary loop as a supplemental loop, passing the other of the stretches of said thread through the bight portion of said 20 supplemental loop, and drawing said thread taut, said bights being piled one against the other, and said last-named stretch drawn as a bight partway into said bight of said primary loop and against the material.

25 12. The method of forming a knotted stitch which consists in passing a loop of thread in reverse directions through the material as a primary loop comprising a pair of stretches, passing one of the stretches 30 of said thread through the bight portion of said primary loop as a supplemental loop, passing the other of the stretches of said thread through the bight portion of said supplemental loop, and drawing said thread 35 taut, said bights being piled one against the other, said last-named stretch drawn as a bight partway into said bight of said primary loop and against the material, and the stretches of said supplemental loop drawn

as bights by the bight of said primary loop 40 partway into the hole in the material through which said primary loop passes.

13. The method of forming a knotted stitch from a single thread, which consists in holding one end of said thread, passing 45 said thread as a loop comprising a pair of stretches in reverse directions through the material, passing one of the stretches of said thread through the bight portion of said primary loop as a supplemental loop, 50 passing the other of the stretches of said thread through the bight portion of said supplemental loop, and drawing the thread taut for forming a knot comprising the bights of said loops and said other of said 55 stretches in knotted relation.

14. The method of forming a knotted stitch from a single thread, which consists in holding one end of said thread, passing said thread as a loop comprising a pair of 60 stretches in reverse directions through the material, passing one of the stretches of said thread through the bight portion of said primary loop as a supplemental loop, passing the other of the stretches of said thread 65 through the bight portion of said supplemental loop, drawing the thread taut for forming a knot comprising the bights of said loops and said other of said stretches in 70 knotted relation and snipping the free ends of said thread.

In testimony whereof, I have hereunto signed my name in the presence of two subscribing witnesses.

WILLIAM F. LAUTENSCHLAGER.
